UNITED STATES PATENT OFFICE

116,206

DESIGN FOR AN AIRPLANE

John D. McKellar, San Luis Obispo, Calif.

Application November 10, 1938, Serial No. 81,021

Term of patent 7 years

To all whom it may concern:

Be it known that I, John D. McKellar, a citizen of the United States, residing at San Luis Obispo, California, have invented a new, original, and ornamental Design for an Airplane, of which the following is a specification reference being had therein to the accompanying drawings, forming part thereof.

In the accompanying drawings:

Fig. 1 is a top plan view.
Fig. 2 is a front elevational view.
Fig. 3 is a side elevational view, and
Fig. 4 is a bottom plan view of an airplane showing my new design.

I claim:

The ornamental design for an airplane, as shown.

JOHN D. McKELLAR.
